UNITED STATES PATENT OFFICE.

MATT GRISAK, OF DUBOIS, PENNSYLVANIA.

RAIL SPLICER.

1,418,915.

Specification of Letters Patent. Patented June 6, 1922.

Application filed April 8, 1922. Serial No. 550,743.

To all whom it may concern:

Be it known that I, MATT GRISAK, a citizen of the United States, residing at Dubois, in the county of Clearfield and State of Pennsylvania, have invented certain new and useful Improvements in Rail Splicers, of which the following is a specification, reference being had therein to the accompanying drawings.

10 This invention relates to splice joints for rails and has for an object to provide a type of rail joint which may be used in the manner in which ordinary rail joints are used, but which is intended more especially for 15 temporary joining and connection of broken rails to permit the passage of cars thereover until permanent repairs can be made.

A further object of the invention is to provide a rail joint having a chair for supporting the contiguous ends of the rail to be joined, with means for clamping the opposite sides of the rails including the clamping of the base, the web and the head of the rail, and with a wedge member insertible to force 25 the rail clamping parts together, and means to lock the wedge removably in such wedging position.

20 A further object of the invention is to provide an improvement upon Patent #1,364,30 750, issued January 4, 1921, and providing in such improvement means for locking the wedging member in locked or wedged position.

With these and other objects in view the 35 invention comprises certain novel parts, units, elements, combinations, constructions and functions, as disclosed in the drawings, together with mechanical equivalents thereof, as will be hereinafter more fully described and claimed.

40 In the drawings:

Figure 1 is a perspective view of the improved rail joint shown upon the contiguous ends of a broken rail and in locked position;

45 Figure 2 is a transverse sectional view taken on line 2—2 of Figure 1;

Figure 3 is a view of the device in side elevation, as indicated by arrow 3 at Figures 1 and 2;

50 Figure 4 is a horizontal sectional view taken on line 4—4 of Figure 3;

Figure 5 is a perspective view of the wedge member showing the lock-receiving 55 recess;

Figure 6 is a perspective view of the implement for withdrawing the lock and permitting the dis-assembling of the parts.

Like characters of reference indicate corresponding parts throughout the several views.

The improved rail splice joint which forms the subject matter of this application comprises a chair 10 of such proportion as to engage upon the under side of the base 65 11 of the rail ends, which may be of the usual and ordinary type of abutting rail ends, or a broken rail, as indicated at 12.

Along one edge of the chair 10 a shoulder 13 is provided of such proportion that at 70 14 it engages under the head 15 of the rail with a side 16 engaging against the flange 17 of the rail with an inclined part 18 engaging along the upper or inclined surface of the base 11.

75 Along the opposite side of the chair 10 an abutment 19 is provided having an under cut or tapered shoulder 20. A clamping member indicated as an entirety at 21 is provided having means for engaging the 80 side of the rail opposite the member 13 corresponding thereto in all particulars and provided with a V-shaped groove 22 between which and the tapered shoulder 20 a tapered space is provided for the receipt of the tapered wedge member 23.

85 This tapered wedge member 23 is shown in perspective at Figure 5 and is provided with a shoulder 24 having inclined sides complementary to the V-shaped groove 22 of 90 the member 21. As indicated more particularly at Figures 1 and 4 this wedge member may be driven between the abutment 19 and the clamping member 21, clamping thereby the said clamping member rigidly and 95 firmly against the rail. To prevent longitudinal movement of the clamping member 21 lugs 25 are provided engaging in slots 26 in the chair 10. This permits lateral movement of the member 21 for clamping purposes while preventing longitudinal movement which might be produced by the passage of cars over the rail.

100 When the splice is made at the abutting ends of rails in the usual manner, dowels 105 27 are inserted through the openings of the holes usually found in such extremities and their ends are seated in sockets 28 and 29 formed respectively in the members 21 and 13. This provides an additional lock to 110

prevent longitudinal movement of the member 21 also preventing the separating of the rail ends. When, however, the device is used simply as a temporary splice for a 5 broken rail the dowels 27 are omitted unless holes are available for that purpose, which is not usual and the device is simply clamped upon the splice of the rail for maintaining the abutting broken ends in alignment for 10 temporary use.

Perforations 30 are formed through the abutment 19 so that in case the device is placed upon a tie, bolts 31 may be inserted through the perforations 30 and through recesses 32 in the edge of the wedge member 23, which will lock this wedge member against retro-active movement.

As, however, the device is used many times in places where it is impossible or inconvenient to nail to a tie, means is provided which forms the subject matter of this application for locking this wedge member 23 in position to retain this wedging action until manually removed. This locking means 20 comprises a sliding bolt 33 seated in a socket 34 in the abutment 19 and actuated by a spring 35. The bolt 33 is provided with an inclined end or extremity 36 to facilitate the insertion of the wedge member 23 which 25 slides along the inclined or tapered side of such wedge member until the recess 36' comes into position for engagement by such bolt, whereupon the spring 35 forces the bolt 33 into such position to engage the wedge member 23 and prevent return movement. 30 35

As the device is used principally as a temporary repair, means is provided for releasing the bolt 33 from such a locking engagement. This comprises a slot 37 formed in the under side of and in transverse relation to the chair and in registry with a socket 38 formed in the bolt 33.

An implement is provided for actuating this spring bolt 33 comprising a hook 39 formed adjacent the end of the bar 40 which is pivoted at 41 to the lever 42. The length of the arm 40 is such that the lever 42 engages the outer edge of the abutment 19 and when the lever 42 is moved in the direction indicated by the arrow at Figure 2 the arm 40 forces the hook 39 toward the edge of the abutment 19, drawing the bolt 33 out of engagement with the socket 36'. The bolt 33 is provided with a head 43 normally engaging the outer edge of the abutment 19 and when the bolt has been drawn outwardly by moving the lever in the direction indicated by the arrow at Figure 2 the head will be spaced away from the edge of the abutment 19, as indicated at Figure 4, which permits a keeper in the form of a staple 44 between the head and the abutment, as shown at Figures 3 and 4 which retains the bolt out of engagement. For the reason that it is

necessary to manipulate the keeper 44 it is necessary to set the removing implement, consisting of the lever 42 and arm 40 at an angle, as indicated at Figure 3.

The extremity of the lever 42 is sharpened 70 or tapered as indicated at 45 to be inserted through the loop of the staple 44 for the purpose of withdrawing the staple from its position as keeper when the sliding bolt 33 is to be released. 75

In operation the adjacent ends of the rail will be brought together either in usual abutting position or any position attained by the break, as indicated in Figure 1, and the chair 10 then lifted from the under side 30 upwardly about the rail and moved laterally until the shoulder 16 engages the flange 17 of the rail. The member 21 is now put in position and the wedge member inserted, being driven home by the use of a hammer 85 or other implement until the wedge is locked by the sliding bolt 33. If this is positioned upon a tie it may be further locked by the insertion of the spikes 31 through the perforations 30, but such locking is intended 90 principally for permanent rather than temporary use.

To release the device from the rails the implement shown at Figure 6 is applied in the position shown at Figures 2 and 3, the lever moved in the direction indicated by the arrow, withdrawing the bolt 33 from engagement with the recess 36', the wedge member 23 being then driven out by a hammer in the direction opposite to its clamping movement, whereby the device will drop of its own weight from the rail. 95 100

What I claim to be new is:

1. A rail splice joint comprising a chair having a permanent abutment along one side conformed complementary to the rail to which it is to be applied and an abutment along the opposite side spaced away from the position of the rail and provided with an under-cut, an abutment sliding laterally relative to the rail and tending to engage the rail opposite the first-mentioned permanent abutment and provided with a groove, the proximate sides of the last two mentioned abutments forming a tapered wedge-way, a wedge formed to slide into the wedge-way and clamp one abutment against the rail, exerting stress upon the other two permanent abutments, said chair being provided with a laterally-extending slot in its under side, a spring-pressed sliding bolt mounted in the chair and engaging a recess in the wedge, said sliding bolt having a recess registering with the slot in the chair providing means for inserting a hooked implement through the slot into the recess to withdraw the sliding bolt from locking engagement. 105 110 115 120 125

2. A rail splice joint comprising a chair having a permanent abutment along one side 130

conformed complementary to the rail to which it is to be applied and an abutment along the opposite side spaced away from the position of the rail and provided with 5 an under-cut, an abutment sliding laterally relative to the rail and tending to engage the rail opposite the first-mentioned permanent abutment and provided with a groove, the proximate sides of the last two mentioned abutments forming a tapered wedge-way, a wedge formed to slide into the wedge-way and clamp one abutment against the rail, exerting stress upon the other two permanent abutments, said chair being provided with a laterally-extending slot in its 10 under side, a spring-pressed sliding bolt

mounted in the chair and engaging a recess in the wedge, said sliding bolt having a recess registering with the slot in the chair providing means for inserting a hooked implement through the slot into the recess to withdraw the sliding bolt from locking engagement, and a head formed upon the exterior end of the sliding bolt providing, when withdrawn, space to insert a keeper 20 between the head and the abutment to retain the sliding bolt in withdrawn position.

In testimony whereof I hereunto affix my signature.

MATT GRISAK.
